UNITED STATES PATENT OFFICE.

ALBERT W. WILLIAMS, OF ST. LOUIS, MISSOURI.

NECKTIE AND RIBBON PRESSING DEVICE.

1,170,379.

Specification of Letters Patent.

Patented Feb. 1, 1916.

Application filed December 24, 1914. Serial No. 878,946.

To all whom it may concern:

Be it known that I, ALBERT W. WILLIAMS, a citizen of the United States, residing at the city of St. Louis, in the State of Missouri, have invented certain new and useful Improvements in Necktie and Ribbon Pressing Devices; and I do declare the following to be a full, clear, and exact description of the invention, such as will enable others skilled in the art to which it appertains to make and use the same.

My invention relates broadly to improvements in pressing devices and more particularly to an article of this character which is designed to press neckties and ribbons.

The object of the invention is to provide a comparatively simple device which will effectively remove all wrinkles from neckties or ribbons and which may be simply and inexpensively manufactured and marketed.

With the above and minor objects in view, the invention resides in certain novel features of construction and combination herein described and claimed and shown in the drawings wherein:

Figure 1 is a front elevation of a device constructed in accordance with my invention; Fig. 2 is a rear elevation thereof; Figs. 3 and 4 are end views; Fig. 5 is a transverse section as seen on the line 5—5 of Fig. 1; Fig. 6 is a bottom plan view; and Fig. 7 is a detail vertical section as seen along the plane of the line 7—7 of Fig. 6.

In these drawings, constituting a part of this application, the numeral 1 designates an upright rectangular frame in the upright side bars of which a pair of horizontal stub shafts 2 are revolubly mounted, one of said shafts being provided with an appropriate form of crank 3. Rigidly mounted on the shafts 2, is a cylindrical roller or reel 4, this reel having a longitudinal groove 5 in its periphery and one wall of this groove being provided with a clamping strip 6 which co-acts with a clamping bar 7 which is movable radially in said groove and which is carried by a pair of curved spring arms 8, the latter being secured at their free ends to the opposite end portions of the reel. These end portions of the roller are preferably reduced in size, where the spring arms 8 contact therewith in order that said arms may lie flush with the periphery thereof.

The strip 6 and the clamping bar 7 constitute means for connecting one end of a tie or ribbon to the reel 4, said bar being

capable of being moved outwardly against the tension of the spring arms 8 by the provision of a headed pin 9 which slides within an opening formed diametrically through the reel. By pushing the head of this button inwardly, the bar will be pushed outwardly, thereby allowing the free end of the tie or ribbon to be inserted beneath the same.

Projecting outwardly from the upper ends of the side bars of the frame 1, is a pair of arms 10 whose outer ends are bent to form coil springs 11, the free ends of the latter being continued downwardly in the form of movable arms 12. The free ends of these arms 12 are rigidly secured to the opposite ends of a pressing bar 13 which lies parallel with the reel and contacts therewith, when no article is clamped within the device. It will be understood that the tension of the coil springs 11 is exerted to normally move this bar 13 inwardly toward the reel.

Rising through one end of the lower side bar of the frame 1, is an upright bolt 14 whose lower end is formed integrally with one end of a coil 15, the other end of said coil being continued to form a horizontal guide arm 16 which lies directly beneath said bar and which normally has its free end seated between the parallel arms of a U-shaped clip 17 which depends from the opposite end of said bar, said free end being preferably turned downwardly as shown. Adjustable longitudinally on the arm 16 is a pair of guide rollers 18 whose upper edges are adapted to travel in a groove 19 formed in the lower side of the bottom bar of the frame.

With the parts constructed as above described, one end of a tie or ribbon T may be inserted beneath the clamping bar 7, this article being then trained beneath the pressing bar 13 and beneath the lower bar of the frame, the guide arm 16 having been previously swung downwardly out of the clip 17 as seen in dotted lines in Fig. 1, and laterally to the position seen in dotted lines in Fig. 6. This arm is then again swung to its normal position and the guide rollers 18 are adjusted longitudinally thereon until they contact with the opposite edges of the article. The crank 3 is now rotated, thus winding the tie or ribbon upon the reel 4 during which operation, the pressing bar 13 contacts yieldably with the article, thus pressing all wrinkles and creases, which will be entirely removed if the article is allowed

to remain upon the device for a number of hours.

From the foregoing description, taken in connection with the accompanying drawings, it will be seen that a comparatively simple device has been provided for carrying out the objects of the invention, yet that the efficiency thereof will not be impaired by such simplicity.

10 I claim:

1. A device of the class described comprising a cylindrical reel having a longitudinal groove in its periphery, a clamping bar in said groove, a pair of curved spring arms 15 secured to the periphery of said reel and to the ends of said bar, a transverse pin sliding diametrically through the reel and abutting the under side of said clamping bar, whereby it may be forced outwardly, and a 20 pressing device adjacent said reel.

2. The combination with a reel upon which an article to be pressed is to be wound, and a pressing device adjacent said reel, of a fixed and a movable guide bar lying 25 parallel to each other and between which the article to be pressed is adapted to be

passed, the movable bar being pivotally connected to the fixed bar, means to normally retain the two bars in fixed relation, and a pair of stops on the movable bar, one 30 of said stops being adjustable longitudinally on said movable bar.

3. A device of the class described comprising a rectangular frame, a winding roller rotatably mounted therein and having 35 an actuating crank and means for the attachment of the object to be wound, and a guide bar lying parallel to one side of the frame and to the axis of the roller, said bar having one end anchored to the aforesaid 40 side of the frame and being coiled adjacent said end whereby to impart resiliency thereto, to allow the bar to yield toward and away from the frame.

In testimony whereof I have hereunto set 45 my hand in presence of two subscribing witnesses.

ALBERT W. WILLIAMS.
